W. D. KMENTT,
HEEL MOLD WASHERING DEVICE,
APPLICATION FILED AUG. 4, 1921.

1,407,757.

Patented Feb. 28, 1922.

UNITED STATES PATENT OFFICE.

WALDEMAR D. KMENTT, OF AKRON, OHIO, ASSIGNOR TO THE B. F. GOODRICH COMPANY, OF NEW YORK, N. Y., A CORPORATION OF NEW YORK.

HEEL-MOLD-WASHERING DEVICE.

1,407,757.

Specification of Letters Patent. Patented Feb. 28, 1922.

Application filed August 4, 1921. Serial No. 489,794.

To all whom it may concern:

Be it known that I, WALDEMAR D. KMENTT, a citizen of the United States, residing at Akron, in the county of Summit and State 5 of Ohio, have invented a certain new and useful Heel-Mold-Washer Device, of which the following is a specification.

This invention relates to means for accurately positioning a large number of small 10 articles, an example being the placing of washers upon heel mold pins preparatory to the molding and vulcanizing of rubber heels wherein the washers are imbedded to serve as abutments for the heads of the nails by 15 which the heel is secured to the shoe.

Machines heretofore devised for this purpose have not proved entirely satisfactory, and it is the object of my invention to overcome their defects by the provision of an 20 appliance which is both rapid and accurate in its operation and is adapted to be made in a compact, readily portable form, my invention in some aspects being an improvement upon the type of device shown in patent 25 to Olin, No. 1,159,077 of Nov. 2, 1915.

Of the accompanying drawings:

Fig. 1 is a plan view of a preferred embodiment of my invention.

Fig. 2 is a vertical section on line 2—2 of 30 Fig. 1, showing the parts at one stage of the operation.

Fig. 3 is a similar view of the device in 35 position upon a mold, showing another stage of the operation.

Fig. 4 is a horizontal section on line 4—4 of Fig. 2, showing an intermediate stage 40 of the operation.

Referring to the drawings, 10 is a cylindrical casing, provided with a handle 11 and 45 with a bottom or base-member 12 formed with a guide-boss 13 adapted to fit into the heel cavity 14 of a mold 15 to position the device, said casing and base-member constituting a frame structure. Said base member 12 is formed with holes 16, 16 of sufficient size freely to permit the passage and 50 lateral play of guide tubes 17, 17 suspended from parts of the device presently to be described, said guide tubes being internally 55 beveled at their bottoms to fit the conical bases of the mold-pins 18, 18 (Fig. 4) and thus adapted to be individually guided into position upon said pins, and preferably weighted at their lower ends, as is indicated 60 by their thickened walls, to facilitate their

settling in place upon the pins. 19 is a washer in molding position upon one of the pins.

Within the casing 10 is fitted a cylindrical slide 20, which may be formed of tubing, 60 the upper portion of said slide being vertically slotted at 20^a to embrace the arms of a spider 21 fixed in the top of the casing 10, for guiding said slide and other parts.

Within the slide 20 is secured a bottom or 65 base-plate 22 formed with holes 23, 23 of sufficient size to permit the passage and limited lateral play of the upper ends of the guide-tubes 17, which are formed with external flanges 24, 24 of larger diameter than 70 said holes, to limit their upward movement relative to said base-plate. Secured within the slide 20, just above the guide tubes 17, is a relatively-thick plate 25 formed with 75 downwardly and inwardly inclined washer-guiding apertures 26, 26 whose upper ends are in two circular series and whose lower ends are located directly over the mouths of the guide-tubes 17, which latter are flared, as shown, to facilitate the entrance of the 80 washers. Secured within the slide 20, above the plate 25, and spaced therefrom to accommodate a thin oscillatory transfer plate or slide 27, is a magazine bottom-plate 28 formed with two circular series of apertures 85 29, 29, 30, 30, circumferentially aligned with and offset from the guide apertures 26 in the plate 25, each aperture being adapted to hold a stack of washers as indicated at 31, Fig. 2. The magazine bottom-plate 28 is 90 also formed upon its upper face with an annular flange or ridge 32, separating the two circular series of apertures 29, 30, for directing the washers into said apertures, and on its bottom face is formed with shallow, annular channels 33, 33 connecting the respective apertures in each series and permitting the transfer of the washers from the magazine apertures 29, 30 to the discharge apertures 26 by the oscillatory transfer plate 27, 100

which latter preferably is of less thickness than the thinnest washers used, in order to avoid engaging more than one washer at a time and choking the device, the channels 33 being of such depth as not to permit the passage of more than one washer of any thickness used.

The transfer plate 27 is formed with apertures 27^a, 27^a, slightly larger in diameter than the washers, and may be moved to reg- 110

ister said apertures with the magazine apertures 29, 30 or with the guide apertures 26. Said transfer plate is centrally secured to a hollow shaft or sleeve 34 rotatably stepped 5 in a counter-bore at the center of the plate 25. This sleeve is formed near its upper end with helical cam grooves 35, 35 coaxing with cam rollers 36, 36 on the spider 21, in which said sleeve is also journaled, to turn 10 the sleeve and the transfer plate 27 as the slide 20 is raised and lowered with respect to the casing 10. Also secured to the sleeve 34 is an oscillatory, annular, webbed agitator or paddle 37, rotatably fitting the interior 15 of the slide 20 and marginally formed with an inwardly sloping base flange 38 for directing the washers into the magazine apertures 29, 30.

Extending through the sleeve 34 and the 20 plates 25, 22, is a side-bolt 39 having secured upon its upper end a hand knob 40 adapted to abut against a nut 41 on the bolt to lift the latter and also adapted to bear upon the top of the sleeve 34 and force the 25 latter, the slide 20, and the parts carried thereby, downward in the casing 10. The bolt 39 is formed with a squared portion 39^a sliding in square apertures in the plates 22 and 25, to prevent its rotation and that of 30 a disc 42 secured upon the bottom of said bolt, this disc being formed with holes loosely enclosing the respective guide-tubes 17 and adapted to abut the flanges 24 on the latter to clamp said guide-tubes in position 35 against the bottom plate 22 of the slide 20 and raise the latter in the casing 10.

In the operation of the device a supply of washers is placed in the upper part of the 40 slide 20, constituting the magazine, and the hand-knob 40 is raised, which first lifts the bolt 39 relatively to the sleeve 34 to raise the disc 42 and thereby clamp the guide-tubes 17 against the plate 22. The further raising of the hand-knob 40, by contact of 45 the flanges 24 with said plate, raises said slide and the sleeve 34 seated thereon, relatively to the casing 10, which meanwhile is held down by the handle 11. Thereby, through the cam action of the grooves 35 and rollers 36, a rotation of nearly 90 degrees is given to the sleeve 34, the transfer plate 27 and the agitator 37, agitating the washers in the magazine to cause them to form in stacks in the magazine apertures 29, 50 and bringing the several apertures of the transfer plate into registry with those of the magazine plate to receive therefrom the lowermost washer of each stack. I prefer to have the magazine apertures 29 and the 55 discharge apertures 26 spaced a substantial distance apart, in order to secure a substantial movement of the agitator. With the hand-knob 40 and the slide 20 elevated, the entire device is then placed upon a mold 60 cavity, the boss 13 entering therein to posi-

tion the device as a whole, and the hand knob is then forced downward, first unclamping the guide tubes 17 and lowering them toward the mold pins in advance of the slide. Further downward movement of the hand knob 70 40, now in contact with the sleeve 34, forces the slide 20 downward until the guide-tubes settle in position on the pins 18, the beveled walls of the former coaxing with the conical bases of the latter to position the tubes, 75 and the base plate 22 thereafter seats upon the flanges 24 of the guide tubes 17 and clamps the latter in the position they have assumed upon the pins. At approximately the same time, the lowering of the slide 20 80 and consequent turning of the sleeve 34 and transfer plate 27 brings the respective apertures of said transfer plate into registry with the respective discharge apertures 26, dropping therein the washers 19, which slide 85 down the discharge apertures and the guide tubes 17 onto the pins.

The hand-knob 40 is then lifted while the frame structure is still held in position upon the mold cavity by the handle 11. The 90 disc 42, first rising with respect to the slide, clamps the guide-tubes 17 against the slide in the relative positions which have been given them by the conical pin bases, and further lifting of the hand-knob 40 carries the 95 slide and said guide-tubes upward in those relative positions, while the frame structure is still held in place upon the mold cavity, the tubes being thus accurately guided as they are lifted from the pins, in order not to 100 knock the washers therefrom.

Various modifications may be resorted to without departing from the scope of my invention and I do not wholly limit my claims to the specific embodiment shown. 105

I claim:

1. A device for placing washers on mold pins, said device having means for registering it with a mold cavity, and having a set of guides adapted to locate the washers on the pins, said guides being separately movable on said device and adapted automatically to register themselves individually with the respective pins. 110

2. A device for placing washers on mold pins, said device having means for registering it with a mold cavity, and having a set of guides adapted to locate the washers on the pins, said guides being separately movable on said device and adapted automatically to register themselves individually with the respective pins, and automatic means for dropping washers into said guides. 120

3. The combination of a heel mold having pins provided with guide-positioning portions, and a washer-placing device having a set of individually movable washer-guides coaxing with said portions to register the guides individually with the respective pins. 125

4. A device for placing washers on heel 130

5 mold pins comprising a set of separately movable guide-tubes adapted to be positioned individually with respect to said pins, and means for clamping said guide-tubes in the relative positions corresponding to the positions of said pins.

10 5. In a device of the class described, the combination of a base-member having a guiding surface adapted to position it on a mold, a washer-guiding member having a mold-engaging surface adapted to move it relatively to said base member to register it with a mold pin, and means for raising and lowering said washer-guiding member relatively to said base-member.

15 6. In a device of the class described, the combination of a base-member having a guiding surface adapted to position it on a mold, separately movable washer-guiding members adapted automatically to register themselves individually with the mold pins, means for raising and lowering said washer-guiding members relatively to said base-member, and automatic means for dropping washers into said washer-guiding members.

20 7. The combination with a heel mold having mold-pins, of a washer-placing device having a frame structure provided with means for registering it with the mold cavity, a set of separately movable guide-members adapted to guide the washers onto the pins, means for individually registering said guide-members with the respective pins, and means for raising and lowering said guide-members relatively to said frame structure.

25 8. The combination of a mold having pins provided with substantially conical bases, and a washer-placing device having a set of separately movable washer-guiding tubes coating with said bases to register said tubes individually therewith, and means for clamping the tubes in the relative positions determined by said bases.

30 9. A heel-mold washering device having an operating handle, a set of separately movable washer-guides automatically self-registering with the mold pins, laterally thereof, washer-feeding means, and connections from said handle for successively registering the guides and operating the washer-feeding means.

35 10. A device for placing washers on heel-mold pins comprising a frame structure adapted to seat upon a mold cavity, a slide mounted in said frame structure, and a set of washer-guiding members pendularly supported from said slide and provided with guiding surfaces adapted to position them individually upon the pins.

40 11. A device for placing washers on mold pins comprising a frame structure adapted to seat upon a mold cavity, a slide mounted therein, a set of washer-guiding tubes shiftably mounted upon said slide and adapted to position themselves upon the pins, and

means for clamping said washer-guiding tubes in relative positions corresponding to those of the pins.

45 12. In a device for placing washers or mold pins, the combination of a frame structure adapted to seat upon a mold cavity, a slide mounted therein, and a set of washer-guiding tubes, suspended from said slide and adapted to position themselves upon the pins as said slide is lowered before the latter reaches its lowermost position.

50 13. A device for placing washers on mold pins comprising a base-member adapted to seat in a mold cavity, a set of guide tubes movable with respect to said base member and adapted automatically to position themselves with respect to said pins, and means upon said base-member for clamping said guide tubes in the relative positions so acquired.

55 14. In a device for placing washers on mold pins, the combination of a frame structure adapted to seat upon a mold cavity, a slide mounted therein, and a set of self-positioning, washer-guiding tubes formed with external projections and a member formed with apertures enclosing said tubes and adapted to abut said projections to clamp said tubes against said slide.

60 15. A device for placing washers on mold pins comprising a base-member adapted to seat in a mold cavity, a self-positioning guide tube movable with respect to said base-member and formed with an external projection, and a vertically slidable member formed with an aperture loosely enclosing said guide tube and adapted to abut said projection to lift said guide tube relatively to said base member.

65 16. A device for placing washers on heel-mold pins comprising a member adapted to be positioned over a heel-mold cavity and formed with washer-discharging apertures, a washer-transferring plate thereon formed with apertures registerable with those of said member, and self-positioning guide tubes adapted to receive washers from the apertures of said member.

70 17. A device for placing washers on mold pins comprising a frame structure adapted to seat upon a mold cavity, a slide mounted in said frame structure, and a set of individually self-positioning guide tubes carried by said slide and adapted to be lowered onto and removed from the mold pins while said frame structure is seated and to be clamped between said slide and the mold.

75 18. A device of the class described comprising a frame structure, a slide mounted therein, a magazine plate fixed to said slide and formed with a magazine aperture adapted to hold a stack of washers, a discharge plate fixed to said slide below said magazine plate and formed with a washer-discharging aperture out of registry with that

of said magazine plate, and means for transferring washers from said magazine aperture to said washer-discharging aperture.

19. A device of the class described comprising a frame structure, a slide mounted therein, a magazine plate fixed to said slide and formed with a magazine aperture adapted to hold a stack of washers, a discharge plate fixed to said slide below said magazine plate and formed with a washer-discharging aperture out of registry with that of said magazine plate, and means for transferring washers from said magazine aperture to said washer-discharging aperture, said means being operated by relative movement of said slide and frame structure.

20. A device of the class described comprising a frame structure, a slide mounted therein, a magazine plate fixed to said slide and formed with an aperture adapted to hold a stack of articles, a discharge plate fixed to said slide below said magazine plate and formed with an aperture out of registry with that of said magazine plate, a sleeve 25 revolvably mounted in said slide, and a

transfer plate secured to said sleeve, extending between the aforementioned plates and formed with an aperture adapted to transfer an article from the aperture of the magazine plate to that of the discharge plate, said hub being provided with a cam surface co-acting with a part of said frame structure to turn said hub and transfer plate.

21. In a device of the class described, the combination of a magazine plate, a transfer plate thereunder, and an agitator above said magazine plate, said transfer plate and agitator being secured to a common hub, and means for oscillating said hub.

22. In a device of the class described, the combination of a magazine plate formed with an aperture and with a ridge adapted to direct articles to said aperture, and an agitator formed with a sloping toe moving along said magazine plate and adapted to direct articles to said aperture.

In witness whereof I have hereunto set my hand this 29 day of July, 1921.

WALDEMAR D. KMENNT
